INSULATOR

Andrew A. Hocher, Etna, Pa., assignor to Hubbard
and Company, a corporation of Pennsylvania

Application September 18, 1936, Serial No. 101,486

14 Claims. (Cl. 174—154)

This invention relates to insulator assemblies, usually referred to in the trade as wire holders, and employed for attaching or securing electric service wires to the walls of buildings or other supports and insulating them therefrom.

The insulator assembly to which my invention relates comprises, in general, an insulator, a metallic base provided with means for securing the insulator thereto, and means such as a lag screw for attaching the assembly to a support.

Insulator assemblies of this type are usually exposed to the weather and for that reason the metallic parts are either galvanized or given some other treatment to prevent rusting. Unless these metallic parts are properly constructed and designed the galvanized surface or protective coating cracks, allowing moisture, oxidizing and other corrosive elements in the air to attack the metal and eventually weaken the structure to the point of failure. Furthermore, the metallic parts in contact with the insulator must be so constructed and designed that they do not impose stresses on the insulator that will break or crack the same. The prior art insulator assemblies known to me have been defective for the reasons above stated, that is, the galvanized or protective surface on the metal parts has cracked and particularly at points subject to high stresses, these points usually being hidden from view but so located as to retain the moisture and thereby accentuate the corrosive or rusting action. These prior art devices also have caused the insulators to fail by reason of the fact that when the load is in a certain direction the insulators are subjected to a wedging action by the metallic parts that causes the insulator to crack or split.

An object of this invention is to provide an insulator assembly of the character referred to above and hereinafter more fully described, that shall be so constructed that cracking of the galvanized or protective surfaces of the metallic parts is prevented and that the insulator will not be subjected to such stresses by the metallic parts as to cause splitting or cracking when the assembly is stressed by the imposed load.

Other objects of the invention will either be pointed out in or understood from the following description taken in conjunction with the accompanying drawing in which:

50 Figure 1 is a view in elevation of an insulator assembly embodying one form of the invention;

Fig. 2 is a view in vertical section of the assembly shown in Fig. 1;

Fig. 3 is a bottom view of the insulator embodied in the assembly of Figs. 1 and 2;

Fig. 4 is a top plan view of the base member of the insulator assembly, and

Figs. 5 and 6 are perspective views of the insulator body and metallic base respectively.

Throughout the drawing and the specification like reference characters indicate like parts.

In Figs. 1 and 2 of the drawing an insulator assembly is shown comprising an insulator body 1, a metallic base 2, and a screw 3, held in place by the base, and means 4 for holding the base and 10 the insulator body in assembled relation to each other.

The insulator body may be of any shape or design and may be made of any material suitable for the purpose. The one illustrated is of an 15 insulating material such as porcelain and is provided with an opening 5 through which a line wire or service wire may be passed preparatory to securing the wire to the insulator. The opening 5 is located substantially at the central portion of the insulator body and the upper surface of such opening is at a substantial distance from the top of the insulator. The insulator body is also provided with an opening 6 extending at substantially right angles to the wire receiving 20 opening 5 and this opening is disposed between the top of the insulator and the wire receiving opening. The means for securing the insulator body to the base extends through opening 6 and downwardly along the insulator body, such means 25 being located in grooves 7 formed in the outer surface of the insulator body, to the base member to which the holding means is secured.

The base member 2 has a substantially flat bottom and an upwardly extending circumferential flange 8 within which the lower end of the insulator is received or nested. The central portion of the base member is provided with an opening 9 through which the screw 3 may be passed.

This opening is preferably of polygonal shape so that it may receive a screw having a correspondingly shaped shank to prevent the screw from turning in the base member. The head 10 of the screw is larger than this opening so that it will not fall through the same. It is preferred that 35 opening 9 be square in form and that the shank portion 11 of the screw that registers with this opening, be of the same shape. The screw and base are given a galvanized or other protective coating and this coating is not broken as a result

40 of strains imposed on the assembly because the parts are not welded or otherwise secured together, nor are the joints between these parts joined by such coating, as each part is galvanized prior to its assembly with the other, and, after 45

50 strains are imposed on the assembly the coating is not broken as a result of the strains imposed on the assembly because the parts are not welded or otherwise secured together, nor are the joints between these parts joined by such coating, as each part is galvanized prior to its assembly with the other, and, after 55

assembly, is free to move relative to each other without breaking the coating.

The bottom of base member 2 is also provided with openings 12 on diametrically opposite sides 5 to receive the securing means 4, these openings being below flange 8.

The securing means shown comprises a length 10 of wire, preferably of heavy gage copper, which is passed through opening 6 and bent to conform to the curvature of the bottom wall thereof and to lie in grooves 7 in the opposite sides of the insulator body. The ends of the wire are bent 15 upwardly into the openings 12, and when so bent hook under the flange of the base, thereby rigidly holding base 2 and insulator 1 together in assembled relation.

In order that the sides of the securing member 4 shall not extend appreciably beyond the outer surface of the insulator body and the base, 20 flange 8 is bent inwardly at openings 12 towards the center thereof so that when the ends of the securing wire are bent to position the portion of the flange engaged thereby is disposed inwardly of the remaining portions of the flange. To accommodate the inwardly projecting portions of the flange and to allow room for the inwardly bent ends of the securing member, the insulator 25 is formed with cavities 14 on diametrically opposite sides and these cavities extend inwardly 30 towards the center of the insulator. Also, the lower end of the insulator that is received in the base member is reduced in diameter as indicated by the boundary line 15 in Fig. 3. The cavities 14 and the grooves 7 in which the securing member lies are shown to be in alignment in Fig. 3. When an insulator assembly is assembled as 35 shown in Figs. 1 and 2, the base is rigidly secured to the insulator and the screw is rigidly secured to the base.

40 If the portions of the flange engaged by the ends of the securing member are distorted by a pulling load whose direction is long the longitudinal axis of the screw, the distortion will be towards shoulder 16 at the bottom of the insulator, but this distortion will not result in a wedging action on the insulator and will not cause it to crack or split. If the load is in the opposite direction and causes the head of the screw to engage the bottom of the insulator, 45 the head of the screw will not impose a wedging or splitting force on the insulator but will only exert a compressive force thereon.

It will also be apparent that a sidewise pull 50 on the insulator assembly of Figs. 1 and 2 will not result in any substantial displacement between the point of contact of the head of the screw and the bottom of the insulator as this contact is substantially at the center of the insulator. The head of the screw will therefore 55 not shift, at least not to any appreciable extent, and therefore cannot exert a wedging action that will tend to split or crack the insulator. If strains are imposed on the assembly of Figs. 1 and 2, to the extent that distortion takes place 60 in the base member, this distortion will not result in the cracking of the galvanized coating of either the screw head, its shank, or of the base. Therefore, if the coating is not cracked, the metal parts will be protected against rust- 65 ing and corrosion.

Having thus described the invention, what I claim as new and desire to secure by Letters Patent is:

70 1. An insulator assembly comprising insula- 75 tor body provided with a substantially central

transverse opening through which a conductor may be passed and a second transverse opening located between said first opening and the top of said insulator body extending at an angle to the longitudinal axis of the first named opening and terminating at its ends in grooves running downwardly to the bottom of the insulator body, a metallic base having a flange embracing a portion of the bottom of said insulator and provided with apertures in its bottom disposed in line with said grooves, a screw having its head locked to and supported by said base, and an element extending through said second named opening and downwardly along said grooves, the ends of said element being bent inwardly and upwardly so as to hook under the flange of said base and hold said insulator body, said base and said screw in assembled relationship.

2. An insulator assembly comprising an insulator body provided with a transverse opening through which a conductor may be passed and a second transverse opening located between said first opening and the top of said insulator body extending at an angle to the longitudinal axis of the first named opening and terminating at its ends in grooves running downwardly to the bottom of the insulator body, the bottom of said insulator body having an inwardly extending locking groove disposed below and inwardly of one of said first-mentioned grooves, a metallic base having a flange embracing a portion of the bottom of said insulator and provided with apertures in its bottom disposed in line with said grooves, said flange having an inwardly extending shoulder positioned to register with said locking groove to hold said base against turning relative to the insulator body, a screw having its head locked to and supported by said base, and a wire tie extending through said second-named opening and downwardly along said grooves, the ends of said tie being bent inwardly and upwardly so as to hook under the flange of said base and hold the insulator body, the base, and screw in assembled relationship.

3. An insulator assembly comprising an insulator body provided with a transverse opening through which a conductor may be passed and a second transverse opening located between said first opening and the top of said insulator body extending at an angle to the longitudinal axis of the first-named opening and terminating at its ends in grooves running downwardly to the bottom of the insulator body, said insulator body having a shoulder disposed below and inwardly of one of said grooves, a metallic base having a flange embracing the bottom of said insulator and provided with apertures in its bottom disposed in line with said grooves, said base having a shoulder disposed to abut said shoulder in the insulator to prevent relative turning of the base and insulator body in one direction, a screw having its head locked to and supported by said base, and a wire tie extending through said second-named opening and downwardly along said grooves, the ends of said tie being bent inwardly and upwardly so as to hook under the flange of said base and hold said insulator body, said base, and said screw in assembled relationship.

4. An insulator assembly comprising an insulator body provided with a substantially central transverse opening through which a conductor may be passed and a second transverse opening located between said first opening and the top of said insulator body extending at an angle to

the longitudinal axis of the first-named opening and terminating at its ends in grooves running downwardly to the bottom of the insulator body, a metallic base having a flange embracing a portion

- 5 of the bottom of said insulator body and provided with apertures in its bottom disposed in line with said grooves, said insulator body and base having means acting to prevent relative turning between them, a screw having its head 10 locked to and supported by said base, and a wire tie extending through said second-named opening and downwardly along said grooves, the ends of said tie being bent inwardly and upwardly so as to hook under the flange of said base and hold said insulator body, said base, and said screw in assembled relationship.

5. An insulator assembly comprising an insulator body provided with a substantially centrally disposed opening therethrough adapted to receive a conductor, a second opening therethrough at right angles to said first opening and between the first opening and the top of the insulator and grooves in the sides of the insulator body extending from said second opening to the bottom, said insulator body being reduced in size near the bottom thereof to form a recess underlying a peripheral shoulder, a base plate for the bottom of said insulator body and having a peripheral flange lying within the recess aforesaid, said base plate being provided with a central polygonal aperture and diametrically opposed slots, a securing screw between said base plate and the bottom of said insulator body and extending through the polygonal opening in said base plate, said securing screw having a portion similar in shape to said polygonal opening, and a hold-down member of U-shape form provided with hook-shaped extremities, said hold-down member passing through said second opening 40 downwardly along said grooves aforesaid and having its hook-shaped extremities passing through the slots in the base plate and interlocked beneath said peripheral flange.

6. An insulator assembly comprising an insulator body having a substantially centrally disposed opening therethrough, a second opening extending at right angles to said first opening and disposed between said first opening and the top of the insulator and opposite side grooves 50 extending from said second opening to the bottom of the insulator body, a base plate substantially co-extensive with the bottom of said insulator body and having an upstanding peripheral flange inwardly bowed at diametrically opposite points, opposed slots located below such inwardly bowed flange points and a central rectangular aperture, a securing screw extending through said rectangular aperture and having a head larger than said aperture disposed between the 55 base plate and the bottom of the insulator body, the securing screw being so shaped where it passes through said rectangular opening as to prevent relative rotation of said plate and screw and a U-shaped hold-down member passing through said second opening in said insulator body and extending downwardly along the sides of the insulator body in the grooves aforesaid, said hold-down member having its extremities passing through said base plate slots and interlocked with said inwardly bowed flange portions 60 to hold said insulator body, said base and said screw in rigid assembled relationship.

7. In an insulator assembly of the kind described, a base plate consisting of a disc-shaped 75 portion having a central polygonal opening,

diametrically opposed slots, and an upstanding peripheral flange having diametrically opposed inwardly bowed portions overlying said slots.

8. In an insulator assembly of the kind described, an insulator body composed of non-conducting refractory material, said insulator body having a substantially centrally disposed opening therethrough adapted to receive a conductor, a second opening at right angles to said first opening and disposed between the top of said first opening and the top of the insulator body and grooves extending from the bottom of said second opening to the bottom of the insulator, said insulator having a reduced bottom portion forming a recess underlying a peripheral shoulder.

9. An insulator assembly comprising an insulating body having conductor and bail openings extending transversely therethrough and being angularly disposed with relation to each other, a metallic base member having a pair of spaced apertures and a peripheral flange which surrounds the adjacent end of the insulating body, a wire bail extending through said bail opening and having its end portions hooked under the peripheral flange of the base member with its extreme ends extending into said apertures and means for securing said base member to a support.

10. An insulator assembly according to claim 9 in which that portion of the insulating body surrounded by the peripheral flange of the metallic base member is reduced in diameter and in which the outer surface of said flange is substantially flush with the surface of the insulating body immediately adjacent thereto.

11. An insulator assembly according to claim 9 in which the insulating body is provided with side grooves extending from the bail hole to its far end which is reduced in diameter to bring the outer surface of the peripheral flange of the metallic base member substantially flush with the surface of the insulating body adjacent thereto.

12. An insulator assembly according to claim 9 in which a threaded member extends through the metallic base member with its head confined between the base of the insulating body and the upper surface of the metallic base member.

13. An insulator assembly comprising an insulating body provided with a transversely extending conductor opening and a transversely extending bail opening between the conductor opening and the top of the body and extending at an angle to the longitudinal axis of the conductor opening, a metallic base member having a flange embracing a portion of the side walls and bottom of the insulating body and having its bottom provided with oppositely positioned openings, a screw supported by said base and having its head confined between said base and the bottom of the insulating body and a wire bail extending through the bail opening and downwardly along the sides of the insulating body with its ends extending over said flange and into said openings in the bottom of the metallic base member.

14. In an insulator assembly, an insulator having a conductor aperture extending therethrough, a surface groove formed therein and extending across the bottom and up the sides of said insulator and spaced from said aperture, a second aperture extending through said insulator at an angle to said first-mentioned aperture, between it and the top of said insulator and

merging with said groove, said insulator having a reduced bottom portion forming an annular recess underlying a peripheral shoulder, a cup-shaped, metal base member enclosing the bottom 5 of said insulator and having its cup-forming flange encircling such reduced portion, a mounting screw projecting through said member in non-rotative engagement therewith with the

head portion thereof located between said member and said insulator, and fastening means extending through said second aperture and lying within said groove for locking said member to said insulator and for positively holding said peripheral shoulder in close association with said cup-forming flange. 5

ANDREW A. HOCHER.

CERTIFICATE OF CORRECTION.

Patent No. 2,174,723.

October 3, 1939.

ANDREW A. HOCHER.

It is hereby certified that error appears in the printed specification of the above numbered patent requiring correction as follows: Page 2, first column, line 42, for the word "long" read along; line 74, claim 1, after "comprising" insert an; and that the said Letters Patent should be read with this correction therein that the same may conform to the record of the case in the Patent Office.

Signed and sealed this 14th day of November, A. D. 1939.

(Seal)

Henry Van Arsdale,
Acting Commissioner of Patents.
